UNITED STATES PATENT OFFICE.

GUSTAV E. HARCKE, OF WATERBURY, CONNECTICUT, ASSIGNEE TO AMERICAN PIN COMPANY, OF WATERBURY, CONNECTICUT, A CORPORATION OF CONNECTICUT.

MACHINE FOR FEEDING SAFETY-PIN SHIELDS AND THE LIKE.

1,119,823.

Specification of Letters Patent.

Patented Dec. 8, 1914.

Application filed May 27, 1913. Serial No. 770,181.

To all whom it may concern:

Be it known that I, GUSTAV E. HARCKE, a citizen of the United States, and a resident of Waterbury, county of New Haven, and State of Connecticut, have invented certain new and useful Improvements in Machines for Feeding Safety-Pin Shields and the Like, of which the following is a full and clear specification.

This invention relates to machines for feeding safety pin shields and the like, the primary object being to provide an improved construction, combination, and arrangement of parts in a machine of this character by means of which the articles can be lifted out of a mass one by one and preferably delivered in a manner which will adapt the feeding mechanism to correlate with other mechanisms in assembling the parts of a completed article of merchandise such for example as a safety pin.

More especially, the present invention contemplates an improved mechanism for feeding safety pin shields in suitable relation to the other parts of safety pins with which they are to be assembled.

Other and further objects will appear in the specification and be pointed out in the appended claims, reference being had to the accompanying drawings in which my invention is exemplified in its adaptation to a safety pin machine.

In the drawings,—Figure 1 is a front elevation of one embodiment of my invention, parts being broken away; Fig. 2 is a top plan view of the same; Fig. 3 is a vertical section of the same, parts being omitted and parts shown in elevation; Fig. 4 is a fragmentary front elevation of the lower portion of the hopper and with the front wall removed; Fig. 5 is a section on the line V—V, Fig. 1, parts being shown in plan; Fig. 6 is a fragmentary rear elevation of the annular gear conveyer; Fig. 7 is a fragmentary front elevation of the cam ring; Fig. 8 is a fragmentary detail section of the annular gear and cam ring; on the line VIII—VIII, Fig. 1; Fig. 9 is a similar section at the top of the ring, certain contiguous parts being shown in elevation; Fig. 10 is a fragmentary front elevation of the gear ring showing interlocked shields; Fig. 11 is a vertical longitudinal section of the chute; Fig. 12 is a plan view of the same; Figs. 13, 14, 15 and 16 are sections

on the lines XIII—XIII, XIV—XIV, XV—XV and XVI—XVI respectively of Fig. 12.

Referring more particularly to the drawings, in the embodiment shown therein a 60 hopper is provided comprising a storage section 1 with a sloping bottom 2, which may be mounted on any suitable support by means of a base flange 3 which is connected to the hopper by means of a web 4 and a 65 delivery portion 5, into which the articles are fed, in the present instance, shields for safety pins. Said portions of the hopper are separated by a partition 6, provided adjacent the bottom of the hopper with an 70 opening 7. The opening 7 may be closed or opened to any desired extent by means of a shutter 8, having a handle 9 which is accessible from above, as shown in Figs. 1 and 3. Within the delivery portion 5 of the hopper, 75 the bottom walls 10 converge in such a way as to cause the shields to fall edgewise into a series of recesses or pockets 11, as shown most clearly in Fig. 4. Said pockets or recesses are comprised in a conveyer which is 80 adapted to remove said shields one by one from the mass and to elevate them to a suitable point of delivery from which they are conveyed by a chute in the manner to be hereinafter explained. Preferably, said conveyer is constructed in the form of an annular gear 12 for the purpose of simplifying 85 its embodiment with a working machine, the present embodiment of said gear being designed to receive its motive power from a 90 worm 13, which is keyed to a shaft 14. Running loosely on one end of the shaft 14 is a pulley 15 which is driven by a belt 16. Said pulley is adapted to transmit power to the shaft 14 by means of a suitable clutch 95 element 17, which coöperates with a clutch element 18 formed integrally with the pulley 15, said clutch element 17 being splined to the shaft 14 in the manner indicated. Simple and efficient means for reciprocating 100 the element 17 of the clutch, is provided by a hand lever 19 which is pivoted at 20 and provided with an upwardly deflected arm with a rounded extremity running in the groove 22 of the clutch element 17. The 105 shaft 14 is journaled in suitable bearings 23 formed in any suitable portion of the frame of the machine. As shown in Figs. 3, 6, 8 and 9, the annular gear 12 is provided with a series of small circular holes 110

24, which are arranged in a circle so that each hole 24 is centrally disposed with respect to a pocket 11. Furthermore, a shield 25 when properly disposed in one of the 5 pockets 11, that is with the rounded end downward, will be in suitable position to have a pin or plunger 26 projected into the rounded central opening in said shield, as shown clearly in Fig. 10. Each of the pins 10 or plungers 26 is rigidly mounted upon a piston 27 of larger diameter than the pin 26, said pistons being reciprocably mounted in correspondingly arranged recesses 28. Between the inner wall of each of said recesses 15 and the pin 27 therein, is disposed a spring 29, the normal tendency of which is to force the piston 27 to the right, according to Figs. 3 and 8, and to retract the pin 26 from engagement with the shield 25 which 20 may be in the socket 11 at the time.

In order to provide simple and efficient means for operating these pistons at suitable intervals in carrying out the purposes of these parts, a cam ring 30, preferably 25 fixed in position, is disposed immediately behind the annular gear 12. As indicated in Fig. 7, the cam ring 30 is adapted to permit the pins or plungers 26 to lie in retracted position throughout approximately three 30 fourths of an entire revolution, the remaining portion 31 being gradually beveled toward the ring gear 12, so that as said gear travels over that portion of the cam rings, the plungers 11 are gradually forced into 35 the sockets or recesses 11. By an inspection of Figs. 1 and 4, it will be understood that after a shield 25 has traveled more than 90° from the position shown in Fig. 4, the plunger 26 will begin to enter the central opening therein, thus preventing the shield from falling out of position during the upper portion of its upward movement. During the 40 first portion of this upward movement, the form of the shield and the pocket 11 co- 45 operate to retain it in position. On the other hand, whenever it happens that the open end of a shield becomes inserted into a socket 11, the plunger 26 during the upper part of its movement, will be forced inwardly without engaging the shield 25, and hence said shield will be free to fall back into the hopper, the purpose of this function of the machine being to deliver the shields to the chute to be hereinafter referred to, with their branch ends extending 50 forwardly in the direction of movement down said chute.

Referring now to Fig. 1, a gear 32 which is of a peculiar form to adapt it to mesh with the ring gear 12, is provided with a rigidly attached rope pulley 33. The gear 32 and pulley 33 are preferably journaled upon a suitable shaft 34 projecting from a bracket 35, as shown in Fig. 3, a portion 5 of the 55 hopper is provided with a bearing boss 36,

within which is a stub shaft 37 for mounting an agitator in the form of a hub 38, from which project a plurality of radial flexible arms 39, said arms being preferably constructed of coiled spring wire to adapt them to drag over the mass of shields without injury to said shields. In this manner, the mass is agitated in a manner suitable to segregate the shields and cause them to drop into the pockets or recesses 11. A grooved 70 pulley 40 is formed solid with the hub 38 to adapt power to be transmitted from the pulley 33, by means of a rope drive 41. Also rigid with the hub 38, is another grooved pulley 42, over which runs a rope or belt 75 43 (see Fig. 1), the rope 43 being adapted to transmit power to a pulley 44 which is journaled in a bracket 45. The pulley 44 is preferably constructed of soft or resilient material, and provided with teeth 46, which 80 as shown in Fig. 9, adapts said toothed pulley to engage the lower one of a pair of interlocked shields 25, it being not uncommon for said shields to become interlocked in the manner illustrated in Fig. 10. It is 85 necessary to embody some such device as this, since should the interlocked shields be discharged into the chute, serious difficulty and probably damage would result therefrom. In order to provide simple and efficient means for preventing shields 25 from 90 being jarred from the plungers 26 after they have been elevated from the hopper, I preferably employ an arcuate plate or strap 47. Said plate 47 terminates adjacent the highest point of the ring gear 12, since at 95 this point the piston 27 has been suddenly released at the end of the beveled portion 31 of cam ring 30 so as to permit the shield which is held by the plungers 26, to drop 100 into the upper end of the chute 48, said chute being suitably arranged to convey the shield forward in the manner now to be pointed out.

Referring now to Figs. 11 to 16 inclusive, the chute 48 is provided with a groove or channel which comprises in the present embodiment, a portion 49 of substantially U-shaped cross section (see Fig. 13), a broadened V-shaped portion 50 (see Fig. 14), a combined U- and V-shaped section 51 (see Fig. 15), and a U-shaped section with an overhanging ledge, as shown at 51' in Fig. 16. As shown in Figs. 12 to 16, as well as certain other figures hereinafter described, each of the shields 25 comprises a relatively light branch 52 and a relatively heavy branch 53. It will furthermore be evident that the feeding mechanism described above, may act to deliver said shields with the 125 heavy branch on either side of the chute 48, as represented by the two adjacently disposed shields at the right of Fig. 12. According to the present embodiment of my invention, the correct arrangement is shown 130

by the shield which is farthest to the right. Said shield therefore retains the position shown as it travels through the chute, inasmuch as the heavier branch thereof sinks 5 into the recess intermediately of the inclines 54 of the section shown in Fig. 14. The other shield which is incorrectly disposed, will likewise travel through the chute with the exception that the lighter branch 52 will 10 slide over the left hand incline when it reaches the V-shaped section 14 of the chute. The last mentioned shield, as it nears that portion of the chute adjacent the section line XV—XV, will however become shifted by 15 reason of the channel or groove in the chute being contracted into the form shown at 51 in Fig. 15, the lighter branch 52 being in consequence of this formation, caused to revolve about the heavier branch 53 into the 20 position shown in Fig. 15. Hence, after the shields have passed the section line XV—XV, all of them will lie in the chute 48 with their branches in the same relative position.

25 What I claim is:

1. In a machine for feeding safety pin shields, the combination of a hopper for the shields to be fed, means for removing said shields from the hopper and discharging them with their branches presented forwardly, and with the branches of some shields in different relative positions than the branches of other shields, and a chute for said shields adapted to arrange them 30 with the branches of each shield in the same predetermined order in which they are applied one by one to safety pin blanks.

2. In a machine for feeding safety pin shields, the combination of a hopper for the shields to be fed, means for discharging said shields from the hopper, said means being adapted to deliver said shields to a chute with their branches presented forwardly thereto, and a chute for receiving the shields 45 discharged from the hopper, said chute being adapted to arrange all of the shields received from said hopper, with their branches in the same relative positions with respect to each other.

50 3. In a machine of the character described, the combination with a hopper for articles to be fed, of a chute into which said articles are to be discharged, means for separately lifting said articles from said receptacle and delivering them to said chute, and means adapted to separate interlocked articles to prevent more than one of said articles being delivered at a time.

60 4. In a machine of the character described, the combination with a hopper for articles to be fed, of a chute into which said articles are to be discharged, means for separately lifting said articles from said receptacle and delivering them to said chute, and means adapted to prevent more than one of 65

said articles being delivered at a time, the last said means being adapted to separate two of said articles which have become locked together.

5. In a machine for feeding articles having branches of different weights, a chute having a surface over which said articles are adapted to slide, said surface being suitably formed to permit the heavier branches of said articles to determine the arrangement of said articles within the chute, said chute comprising one portion adapted to receive said articles with the heavier branches disposed in different relative positions with respect to the lighter branches and another portion adapted to revolve the lighter branches of some of said articles around on said heavier branches to arrange all of said articles with the heavier branches in the same relative positions with respect to the 80 lighter branches.

6. In a machine of the character described, the combination with a hopper, of a chute for safety pin shields with branches of different weights, and means for delivering said shields with the same ends presented to said chute, said chute being adapted to convey said shields with their branches arranged in predetermined order and provided with means for changing the positions of said shields to arrange them when the branches are not in such predetermined order.

7. In a machine of the character described, the combination with means for delivering safety pin shields always with the same end presented, of a chute adapted to receive said shields with their branches out of a predetermined order and provided with means for arranging said shields in such predetermined order.

8. In a machine of the character described, the combination of a hopper, a socket traveling into and out of said hopper, and means for locking an article to be fed in said 100 socket, said means being releasable.

9. In a machine of the character described, a hopper, sockets traveling into and out of said hopper, means for locking articles to be fed, in said sockets, said means being adapted to move into and out of locking position with respect to said sockets.

10. In a machine of the character described, the combination of a hopper and a rotatable annulus in said hopper, said annulus being provided with holding sockets arranged around the inside edge thereof and provided with means for locking articles to be fed within said sockets.

11. In a machine for feeding safety pin 125 shields, the combination with a hopper provided with means for feeding safety pin shields therefrom with the same end presented forwardly and with the branches of said shields dissimilarly arranged, of a 130

chute having walls suitably formed and disposed to arrange all of said shields with their branches in the same predetermined order of arrangement.

5 12. In a machine of the character described, the combination of a hopper, a chute leading therefrom for feeding safety pin shields to a safety pin machine, means for feeding said shields from said hopper to said chute with the same ends presented, and means arranged along said chute for predetermining the positions of the branches of said shields passing therethrough.

15 13. In a machine of the character described, the combination with a hopper, of a rotatable annulus therein, said annulus being provided with sockets for receiving safety pin shields only in a predetermined arrangement, means mounted on said annulus for locking said articles in said sockets, a chute suitably disposed to receive the articles from said sockets, and means for releasing said locking means when the sockets are adjacent to said chute.

25 14. In a machine of the character described, the combination with a hopper for safety pin shields, of a chute leading therefrom, and a conveyer operating between said hopper and chute, said conveyer being provided with relatively movable means adapting it to hold a shield when one end is presented thereto but to be non-effective when the opposite end of said shield is presented thereto.

35 15. In a machine of the character described, the combination with a hopper for safety pin shields, of a conveyer ring provided with sockets for separate shields, and a pin operatively related to each of said 40 sockets, said pin being adapted to retain a shield in said socket to remove it from the hopper and afterward to release said shield.

45 16. In a machine of the character described, the combination with a hopper for safety pin shields, of a conveyer ring provided with sockets for separate shields, and a pin operatively related to each of said 50 sockets, said pin being adapted to retain a shield in said socket to remove it from the hopper and afterward to release said shield, said pin being suitably mounted to be under a normal tendency to release said shield.

55 17. In a machine of the character described, a feeding device for safety pin shields, said device comprising a ring with 60 sockets or recesses arranged around its inner periphery, a pin or plunger reciprocably mounted in the lateral wall of each of said sockets or recesses for releasably engaging said shields, and means for operating said pins or plungers at suitable intervals to engage and release said shields during the feeding operation.

65 18. In a machine of the character described, a feeding device for safety pin

shields, said device comprising a ring with 70 sockets or recesses arranged around its inner periphery, a pin or plunger reciprocably mounted in the lateral wall of each of said sockets or recesses for releasably engaging said shields, and means for operating said pins or plungers at suitable intervals to engage and release said shields during the feeding operation, said means comprising a cam in operative engagement with said pins 75 or plungers.

19. In a machine of the character described, a vertical ring provided with sockets 80 for safety pin shields around its inner periphery, reciprocable plungers arranged transversely of the rim of said ring, said plungers being adapted to engage shields in 85 said sockets and having their ends projecting from said ring, a fixed cam operatively disposed with relation to said plungers, and a chute operatively disposed with respect to the sockets in said ring in their discharging positions.

20. In a machine of the character described, a vertical ring provided with sockets 90 for safety pin shields around its inner periphery, reciprocable plungers arranged transversely of the rim of said ring, said 95 plungers being adapted to engage shields in said sockets and having their ends projecting from said ring, a fixed cam operatively disposed with relation to said plungers, a chute operatively disposed with respect to the sockets in said ring in their discharging positions, and means disposed adjacent the 100 rim of said ring for disengaging other shields which become interlocked with the shields in said sockets.

21. In a machine of the character described, a vertical ring provided with sockets 105 for safety pin shields around its inner periphery, reciprocable plungers arranged transversely of the rim of said ring, said 110 plungers being adapted to engage shields in said sockets and having their ends projecting from said ring, a fixed cam operatively disposed with relation to said plungers, and a chute operatively disposed with respect to the sockets in said ring in their discharging positions, said pins being suitably arranged 115 with respect to said sockets so that shields which are deposited with the branch-end innermost in said sockets, will not be engaged by said plungers.

22. In a machine of the character described, a chute adapted to convey safety pin shields embodying relatively heavy and relatively light branches, said chute being provided with a depression into which the heavier branch of said shield is adapted to 125 settle by gravity, and means for displacing the lighter branch of said shield about the heavier branch to reverse the relative position of said branches, said means being operative only upon those shields which have 130

their branches reversely disposed to the required disposition thereof.

23. In a machine of the character described, a chute adapted to convey safety pin shields embodying relatively heavy and light branches, said chute being provided with means for reversing the relative position of the branches of said shields, said means comprising a channel or groove in which one wall is formed to gradually approach the perpendicular, the shield being thereby caused to assume a position in which the lighter branch is uppermost and from which position said lighter branch falls about the heavier branch as a pivot.

24. In a machine of the character described, a chute for conveying safety pin shields with their branches of unequal weight presented forwardly, said chute being provided with a channeled portion with oppositely disposed inclined sides, the heavier branches of said shields being adapted by gravity to seek the depression intermediate of said inclined sides and with the lighter branches respectively engaging said inclined sides, and means for rotating the lighter branch on one of said inclines about the heavier branch to which it is connected.

25. In a machine of the character described, a chute for conveying safety pin shields with their branches of unequal weight presented forwardly, said chute being provided with a channel portion with oppositely disposed inclined sides, the heavier branches of said shields being adapt-

ed by gravity to seek the depression intermediate of said inclined sides and with the lighter branches respectively engaging said inclined sides, and means for rotating the lighter branch on one of said inclines about the heavier branch to which it is connected, said means consisting of another portion of said chute in which the channel is contracted to bring the lighter branch of said shield into a position above the heavier branch thereof, the last said channel being gradually inclined toward the opposite side of said chute to reverse the position of said branches of the shield.

26. In a machine for feeding safety pin shields, a conveyer for safety pin shields, reciprocable plungers suitably mounted on said conveyer to releasably engage said shields, and a cam for operating said plungers.

27. In a machine for feeding safety pin shields, a conveyer for safety pin shields, reciprocable plungers suitably mounted on said conveyer to releasably engage said shields, and a cam for operating said plungers, said cam being fixed adjacent the path of movement of said conveyer and adapted to retain the plungers in shield-engaging position during their travel across said cam, said cam terminating adjacent the point of discharge of said conveyer.

GUSTAV E. HARCKE.
